(57) **CLAIM**

The ornamental design for a base station for robotic vacuum cleaners, as shown and described.

DESCRIPTION

1. Base station for robotic vacuum cleaners

FIG. 1.1 is a front view of a base station for robotic vacuum cleaners

FIG. 1.2 is a rear view

FIG. 1.3 is a left view

FIG. 1.4 is a right view

FIG. 1.5 is a top view

FIG. 1.6 is a bottom view

FIG. 1.7 is a perspective view

The broken lines shown are included for the purpose of illustrating portions of the base station for robotic vacuum cleaners which form no part of the claimed design.
